UNITED STATES PATENT OFFICE.

SARAH A. TIPTON, OF PORTALES, TERRITORY OF NEW MEXICO.

ATTACHMENT FOR STOVEPIPES.

No. 904,377.

Specification of Letters Patent.

Patented Nov. 17, 1908.

Application filed February 28, 1908. Serial No. 418,307.

To all whom it may concern:

Be it known that I, SARAH A. TIPTON, a citizen of the United States, residing at Portales, in the county of Roosevelt and Territory of New Mexico, have invented new and useful Improvements in Attachments for Stovepipes, of which the following is a specification.

This invention relates to an attachment 10 for stove pipes, and the object of the invention is to provide a drum having means whereby it is readily connected between the sections or joints of a stove pipe, said drum being provided with a suitable chamber or 15 oven whereby food may be quickly and readily cooked by the heat provided by the products of combustion emitted through the pipe from the stove to which the pipe is attached.

Another object of the invention is to provide a drum for stove pipes having doors whereby access may be readily obtained to an oven or chamber within the drum, the doors being so constructed and arranged as 25 to provide an effective shelf when the doors are opened.

A further object of the invention is to provide a drum adapted for attachment with the sections of a stove pipe with a flattened 30 top adapted for the reception of cooking utensils, such as pans, kettles and the like.

A still further object of the invention is to provide a drum for stove pipes having a removable chamber or oven and having one 35 of its ends provided with a removable closure whereby the oven may be readily withdrawn from the drum or the interior of the drum cleaned from soot or other products of combustion.

With these and other objects in view the invention resides in the novel construction 40 of elements and their arrangement in operative combination, hereinafter fully described and claimed.

In the drawings, Figure 1 is a central longitudinal section of a device constructed in accordance with my invention. Fig. 2 is a vertical transverse sectional view upon the line 2—2 of Fig. 1. Fig. 3 is an end elevation 45 of the device.

In the accompanying drawings the numeral 1 designates the drum of my improved attachment for stove pipes. The drum 1 is centrally provided with suitable 50 pipe sections or nipples 2, by which it is positioned upon the sections of the stove

pipe. The drum 1 is substantially cylindrical in cross section, but has its top 3 flattened, for the reception of cooking utensils, such as frying pans, kettles or the like. 60 The drum 1 has one of its ends provided with a flange or face portion 4, having its inner ends turned inwardly to provide a bearing face 5, for a removable chamber or oven 6. The opposite end of the drum is 65 entirely open and is adapted for the reception of a substantially annular closure 7. This closure 7 has its perimeter provided with an inturned flange 8 adapted to enter the open end of the drum and fit snugly 70 against the inner surface thereof and the inner edge of said closure is inturned to form a bearing flange 9 corresponding in size and shape with the bearing flange 5 at the opposite end of the drum. The inturned 75 flange 9 of the closure 7 provides a bearing to enter one end of the oven or chamber 6 and the opening in the center of the closure 7, which corresponds with one end of the oven, may be opened or closed by a door 10. 80 The opening provided by the inturned bearing face or flange 5 of the end 4 of the drum is also provided with a suitable door whereby the oven of chamber 6 may be closed at that end of the drum. Each of the doors 10 85 is preferably constructed of suitable sheet metal. Said doors are provided at their tops with sliding latches 11 each mounted within a suitable bearing 12 on the outer face of the door. The latch 11 is provided upon 90 its upper face with an elongated slot 13, adapted for engagement with a slotted lug 14, secured upon the closure 7 or the face 4 of the drum. The latch 11 is provided with a suitable finger 15, by which the latch may 95 be slid within the bearing 12, when it is desired to disconnect the latch from the lug. The door 10 is provided near its lower portion with spaced ears 16, the ends of which are provided with suitable perforations 100 adapted for the reception of suitable pintles, whereby they are pivotally connected with the arms 17 of bracket members 18, secured upon one end of the drum and the closure 7. The arms 17 are provided with suitable off- 105 sets 19, adapted to lie normally beneath the ears 16 when the door is closed and to provide a bearing for the ears 16 when the door is opened, thus effectively holding the door in a substantially horizontal position, whereby it may serve as an effective shelf when 110 opened.

The oven or chamber 6 is open at each end, and is of a size and shape corresponding with the inner faces of the inturned flanges 5 and 9 of the end 4 of the drum and the closure 7. The oven is of a length equaling that of the interior of the drum 1, and is provided with suitable spacing lugs or arms 20, whereby it is effectively spaced away from the inner face of the drum 1 when positioned within the drum. These spacing lugs or arms 20 are preferably constructed of resilient material whereby they will serve as an effective means for at all times keeping the oven properly spaced in its relation with the drum 1. The flanges 5 and 9 also serve as an effective means for retaining the oven 6 in proper position within the drum. The oven 6 is provided with a reinforcing plate 21, positioned upon the lower outer face of the drum directly above the lower thimble 2, and this plate 21 is designed to serve as a means for preventing the interior of the oven being over heated at the point where the products of combustion from the pipe directly contact with the oven and also serves as a means for prolonging the life of the oven. The oven is also provided with a removable shelf 22, constructed in any approved manner and of any desired construction. A plurality of these shelves 22 may be employed if desired, and the flanges 5 and 9 may be provided with suitable brackets whereby the shelves may be sustained within the oven.

From the above description it will be seen that I have provided a simple, cheap and effective oven for stove pipes, one which in no wise interferes with the stove to which the pipes are connected, and one which effectively directs the products of combustion from the stove pipe directly around the oven chamber, thus providing means whereby

great heat is imparted to the oven. It will be also seen that I have provided the drum with a removable oven chamber, and with a removable closure whereby free access to the interior of the drum is readily obtained, and that I have provided the ends of the drum with substantial doors communicating with the oven chamber so arranged and connected as to provide effective shelves when the doors are opened, and that by providing the drum with a flattened top an additional heating surface is provided for the reception of cooking utensils, such as kettles, frying pans and the like.

Having thus fully described the invention what is claimed, as new is:

An attachment for stove pipes comprising a drum having one end open and the opposite end partially closed, said partially closed end having a central opening and an inturned flange around said opening and forming a bearing face, a closure for the opposite end of the drum having an inturned peripheral flange to enter said end of the drum and further provided with a central opening and an inturned flange around said opening and forming a bearing face, an oven chamber in the drum having its ends open and resting on the bearing faces at the ends of the drum, spacing lugs arranged between the oven and the drum, doors for the openings provided by the closure and the end of the drum, and means engaging the doors and drum for normally retaining said doors in a closed position and in a horizontal position when open.

In testimony whereof I affix my signature in presence of two witnesses.

SARAH A. TIPTON.
